[57] CLAIM

The ornamental design for a no spill drinking vessel, as shown and described.

DESCRIPTION

FIG. 1 is a top, front, left perspective view of a no spill drinking vessel showing my new design;

FIG. 2 is a top plan view thereof;

FIG. 3 is a bottom plan view thereof;

FIG. 4 is a front elevational view, the rear elevation view and left and right side elevational views, being mirror images thereof;

FIG. 5 is a top, front, left perspective view of a no spill drinking vessel showing a second embodiment of my new design;

FIG. 6 is a front elevational view of the second embodiment, the rear elevation view and left and right side elevational views being mirror images thereof;

FIG. 7 is a top plan view thereof; and,

FIG. 8 is a bottom plan view thereof.

The broken line showing of a lid in FIG. 1 is for illustrative purposes only and forms no part of the claimed design.

FIG. 1

FIG. 2

FIG. 3

FIG. 4

FIG. 5

FIG. 6

FIG. 7

FIG. 8
